STUD WELDING GUN

Thomas E. Shoup, Amherst, Roger W. Sholle, Lorain,
and Lorenz John Mowry, Elyria, Ohio, assignors to
Gregory Industries, Inc., Detroit, Mich., a corporation
of Michigan

Application December 27, 1954, Serial No. 33,706

Term of patent 14 years

(Cl. D26—1)

FIG. 2

FIG. 3

FIG. 4

Figure 1 is a perspective view of a stud welding gun showing our new design;

Figure 2 is a front elevational view;

Figure 3 is an end view; and

Figure 4 is a sectional view taken along the line 4-4 of Figure 2.

The dominant features of our design reside in the portions shown in full lines.

What we claim is:

The ornamental design for a stud welding gun, substantially as shown and described.
